His Attorney.

UNITED STATES PATENT OFFICE.

ALLEN B. CLARK, OF LEAVENWORTH, KANSAS.

JAR OR CAN HOLDER.

SPECIFICATION forming part of Letters Patent No. 771,969, dated October 11, 1904.

Application filed October 12, 1903. Serial No. 176,725. (No model.)

To all whom it may concern:

Be it known that I, ALLEN B. CLARK, a citizen of the United States, residing at Leavenworth, in the county of Leavenworth and State of Kansas, have invented certain new and useful Improvements in Jar or Can Holders, of which the following is a specification.

My invention relates to improvements in jar or can holders.

10 The object of my invention is to provide a device by means of which a cylindrical can or jar may be embraced and supported.

A further object of my invention is to provide a device by means of which the can or jar may be firmly held while the cover is being screwed thereupon or removed therefrom.

15 My invention provides a clamping-band for encircling and embracing the jar and two levers pivotally connected together, means being provided by which by proper manipulation, as hereinafter described, the clamping-band may be made to firmly grip the can or jar.

Other novel features are hereinafter fully 25 described and claimed.

In the accompanying drawings, illustrative 30 of my invention, Figure 1 is a perspective view showing my can or jar holder applied to an ordinary screw-top jar, the levers being in the position assumed by them when the jar is being held to turn the screw-top thereof. Fig. 2 is a top view of a jar having the holder applied to it in the manner shown in Fig. 1. Fig. 3 is a longitudinal central sectional view 35 of my holder shown detached from the jar. Fig. 4 is a top view similar to that shown in Fig. 2, the levers being shown expanded at their inner ends and in position for carrying the jar.

40 Similar characters of reference indicate similar parts.

1 denotes an ordinary cylindrical jar provided with the common screw-top 2.

3 indicates the clamping-band, comprising 45 a band of flexible material—such as brass, iron, steel, or other metal—and provided near one end with one or more holes 4, adapted to receive therein the inner end of a lever 5, pivotally connected by a transverse pin 6 to a lever 7. The two levers are not crossed; but

the lever 5 is preferably provided with an inwardly - extending projection 8, which is mounted in a recess 9, provided in the lever 7, the pin 6 extending through the projection 8 and the recessed portion of the lever 7 55 at right angles to the said projection. The inner end of the lever 7 is provided with a transverse hole 10, through which is extended and movable lengthwise therein the perforated end of the clamping-band 3, the holes 60 thereof being adapted to be engaged one at a time by the inner end of the lever 5, the same being provided with a shoulder 11 on its outer side to prevent the band slipping too far on the lever 5. The other end of the band 3 is 65 extended through the hole 10 and is folded back upon itself around the end of the lever 7, and thus forms a hinged connection therewith. The folded parts of the band 3 (denoted by 12) are not rigidly secured together, 70 but are left free, so that they may be adjusted through the hole 10, so as to have more or less lap, thus permitting the length of the clamping portion of the band 3 to be varied to suit cans or jars slightly varying in diameter. 75 For greater variation in adjustment and to suit cans or jars varying much in diameter the adjustment may be made by changing the engagement of the lever 5 from one hole 4 to another.

In operating my invention to turn the cover in the direction indicated by the arrow in Fig. 1 for the purpose of unscrewing the cover from the jar the band 3 is slipped over the body of the jar with the lever 7 to the right, 80 as shown in Fig. 1. Then the cover is turned in the direction indicated by the arrow and the lever 7 pulled in the opposite direction. By so pulling the lever 7 the inner end of the lever 5 will be tightly pressed against the 85 folded portion of the band 3, the two levers serving as a single lever, with the inner end of lever 5 acting as the fulcrum. The band 3 will thus be caused to tightly clamp the jar, and slippage of the band will be prevented. 90 To screw the cover in the opposite direction, the levers and band may be reversed in their positions relative to the jar and the levers forced in the opposite direction; but this is not at all necessary, as the jar may with equal 95 100

facility be clamped by compressing the outer ends of the levers 5 and 7 with the hand, thus forcing the inner end of lever 5 away from the inner end of the lever 7 to the positions 5 shown in Fig. 4. When so forced, the inner end of lever 5 will draw the perforated end of the band 3 through the hole 10 in lever 7, thus tightly clamping the jar and permitting the cover to be gripped and turned in either 10 direction. The levers 5 and 7 may be disposed as shown in Fig. 4 when it is desired to use the device simply to support the jar while it is being filled or for carrying it from one place to another.

15 As already described, it is not necessary to place the band 3 upon the jar in one particular manner for turning the cover in either direction, as by compressing the outer ends of the levers 5 and 7 the jar may be tightly 20 clamped and the cover turned in either direction. Care need therefore not be used to place the band on the jar or can in any particular position.

Many modifications may be made in the 25 construction of the device without departing from the spirit of my invention.

Having thus described my invention, what I claim, and desire to secure by Letters Patent, is—

30 1. A can or jar holder comprising two levers pivotally connected together, one arm of one lever having a hole therethrough, and a clamping - band having one end extending through said hole and folded back upon itself 35 so as to embrace the lever, the free end of the clamping-band being extended through said hole and provided with one or more holes for receiving one arm of the other lever which is positioned to bear, when properly swung, upon the folded portion of said band.

2. A can or jar holder comprising two levers pivotally connected together, one arm of one lever having a hole therethrough, and a clamping - band having one end extending

through said hole and folded back upon itself 45 so as to embrace the lever, the folded portion of the band being adjustable to different positions on said lever respecting the extent of the portion folded, the other end of the band being perforated and extending through said 50 hole in said lever, the perforations being adapted to receive the end of the other lever which lever is positioned to bear when properly swung, upon the folded portion of said band.

3. A can or jar holder comprising two levers pivotally connected together, one arm of one lever being provided with a hole therethrough, the corresponding arm of the other lever being provided with a shoulder, and a 60 clamping-band having one or more perforations near one end, said perforated end extending through the hole in one lever, the other end of the band being hinged to the said lever, the shouldered end of the other lever 65 being adapted to enter the perforations of the band, the shoulder limiting the movement of the band on the said lever and said shouldered lever which is positioned to bear, when properly swung, upon the hinged portion of the 70 band.

4. A can or jar holder comprising two levers pivotally connected together, one arm of one lever having a hole therethrough, and a clamping - band having one end extending 75 through said hole and folded back upon itself so as to embrace the lever, the free end of the clamping-band being extended through said hole and provided with means for engagement with the other lever which is positioned, 80 when properly swung, to bear upon the folded portion of the said band.

In testimony whereof I affix my signature in presence of two witnesses.

ALLEN B. CLARK.
